CLAIM

The ornamental design for a throw-away tip for cutting tool, as shown and described.

DESCRIPTION

FIG. 1 is a front view of an embodiment of a throw-away tip for cutting tool showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a first perspective view thereof;

FIG. 8 is a second perspective view thereof;

FIG. 9 is an enlarged view of IX-IX portion of FIG. 1;

FIG. 10 is an enlarged view of X-X portion of FIG. 4;

FIG. 11 is an enlarged view of XI-XI portion of FIG. 4;

FIG. 12 is an enlarged view of XII-XII portion of FIG. 5;

FIG. 13 is an enlarged view of XIII-XIII portion of FIG. 6;

FIG. 14 is a cross sectional view taken along line XIV-XIV of FIG. 9;

FIG. 15 is a cross sectional view taken along line XV-XV of FIG. 9;

FIG. 16 is a cross sectional view taken along line XVI-XVI of FIG. 9; and,

FIG. 17 is a referential view showing the state in which a workpiece is machined with the throw-away tip for cutting tool according to the first embodiment attached to a holder. The broken lines in the drawings depict unclaimed environmental subject matter. The long dashed and short dashed

(Continued)

lines shown in the drawings indicate only a boundary between the claimed portion and the unclaimed portion.
